(57) **CLAIM**

I claim the ornamental design for a lace tightening device, substantially as shown and described.

DESCRIPTION

FIG. 1 is a perspective view of the lace tightening device; FIG. 2 is a front view of the lace tightening device; FIG. 3 is a back view of the lace tightening device; FIG. 4 is a first side view of the lace tightening device; FIG. 5 is a second side view of the lace tightening device; FIG. 6 is a top view of the lace tightening device; and, FIG. 7 is a bottom view of the lace tightening device. The broken lines in the drawings represent portions of the lace tightening device that form no part of the claim.
